US0D1038400S

(12) **United States Design Patent** (10) Patent No.: **US D1,038,400 S**
(45) Date of Patent: ** Aug. 6, 2024

(54) **SURGICAL IMPLANT**

(71) Applicant: **Warsaw Orthopedic, Inc.**, Warsaw, IN (US)

(72) Inventors: **Adriaan J. Kuyler**, Saint Augustine, FL (US); **Benjamin D. Cowan**, Memphis, TN (US); **Anthony J. Melkent**, Germantown, TN (US); **Keith E. Miller**, Germantown, TN (US); **Cristian A. Capote**, Memphis, TN (US); **Jonathan E. Blackwell**, Lakeland, TN (US); **Jennifer B. McNab**, Memphis, TN (US)

(73) Assignee: **WARSAW ORTHOPEDIC, INC.**, Warsaw, IN (US)

(**) Term: **15 Years**

(21) Appl. No.: **29/831,431**

(22) Filed: **Mar. 21, 2022**

Related U.S. Application Data

(62) Division of application No. 29/689,091, filed on Apr. 26, 2019, now Pat. No. Des. 955,579.

(51) **LOC (14) Cl.** **24-03**

(52) **U.S. Cl.**

USPC **D24/155**

FOREIGN PATENT DOCUMENTS

EP	1430858 A1	6/2004
JP	5758485 B2	8/2015

Primary Examiner — Charles D Hanson

(74) Attorney, Agent, or Firm — FOX ROTHSCHILD LLP

(57) **CLAIM**

The ornamental design for a surgical implant, as shown and described.

DESCRIPTION

FIG. 1 is a top, front, right perspective view of a surgical implant according to the present disclosure;

FIG. 2 is a top view of the surgical implant of FIG. 1;

FIG. 3 is a bottom view of the surgical implant of FIG. 1;

FIG. 4 is a front view of the surgical implant of FIG. 1;

FIG. 5 is a back view of the surgical implant of FIG. 1;

FIG. 6 is a right view of the surgical implant of FIG. 1; and,

FIG. 7 is a left view of the surgical implant of FIG. 1.

The broken lines in the figures illustrate portions of the article that form no part of the claimed design.

1 Claim, 2 Drawing Sheets
